(57) **CLAIM**

The ornamental design for a lens for camera, as shown and described.

DESCRIPTION

FIG. 1 is a front perspective view of a lens for camera showing my new design;

FIG. 2 is front elevational view thereof;

FIG. 3 is rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines depict the portions of a lens for camera in which the design is embodied and form no part of the claimed design.
